UNITED STATES PATENT OFFICE.

WILLIAM S. HARPSTER, OF COLUMBUS, OHIO, ASSIGNOR, BY MESNE ASSIGNMENTS,
TO CLARENCE A. HILL, OF COLUMBUS, OHIO.

COMMUNION-SERVICE TRAY.

1,110,051.

Specification of Letters Patent. Patented Sept. 8, 1914.

Application filed April 19, 1911, Serial No. 621,986. Renewed February 5, 1914. Serial No. 816,841.

To all whom it may concern:

Be it known that I, WILLIAM S. HARPSTER, a citizen of the United States, residing at Columbus, in the county of Franklin and State of Ohio, have invented a certain new and useful Improvement in Communion-Service Trays, of which the following is a specification.

The object of this invention is to provide an improved tray for holding individual communion service glasses.

More particularly it is my object to prevent the staining and smearing of the tray or its parts by spilt or overflowing wine and at the same time prevent noise in the handling of the glasses.

The invention is embodied in the features shown in the accompanying drawings, set forth in the following description and then pointed out in the claims.

In the accompanying drawing—Figure 1 is a top plan view of a portion of the tray. Fig. 2 is a vertical section of the tray with the middle portion broken out.

25 A tray for holding the individual service glasses very commonly comprises a pan 3 having an annular shoulder 4 to receive a glass holder, the latter consisting of a plain metal disk having a suitable number of glass 30 receiving openings provided with cushioned sides or pads to prevent noise. In the present invention as shown the glass holder comprises principally two metal disks 5 and 6 of equal size and like form to rest together 35 on the shoulder 4 said disks being provided with vertically coinciding glass admitting apertures of considerably larger diameter than the diameter of the lower portion of the glass, and a disk of card board 7 and a 40 disk of blotting or absorbent paper 8 also provided with apertures but of smaller diameter than that of the apertures in the metal sheets said sheets of card board and absorbent paper being placed together and 45 between the metal disks so that their apertures align axially. By this construction there is left projecting in the opening of the metal sheets a ring of absorbent paper and card board. The apertures in the card board 50 and absorbent paper are made of such size that a glass of slightly tapering form can

be placed and supported therein without the sides of the glass touching the adjacent edges of the metal disk as illustrated in Fig. 2. The four disks just described are bound 55 together by several screws, such as seen at 9, engaging the two metal disks. The absorbent paper takes up wine that may have been left adhering to the sides of the glasses thereby preventing it from smearing the 60 tray or the metal disks. Excess of overflowing wine is absorbed by the absorbent paper even by that which lies between the solid metal parts of the disks. Absorbent paper, which is more commonly known as 65 "blotting" paper when dry is brittle and when moistened becomes soft and pliable hence I employ the card board to brace such paper where it projects beyond the metal part of the holder. When the absorbent 70 paper becomes so far saturated as to be no longer serviceable it, as well as the card board if desired, can be replaced with a fresh one.

What I claim is:

1. In an individual communion service 75 tray, a glass holder including in combination a metal sheet provided with an aperture, a sheet of absorbent paper backed by a sheet of non-absorbent stiff paper, said absorbent sheet being located between said metal sheet 80 and the non-absorbent sheet, said absorbent and non-absorbent sheets provided with apertures of smaller diameter than that of the metal sheet and all of said apertures coinciding vertically, and means for holding 85 said sheets together, substantially as described.

2. In an individual communion service tray, a glass holder including two flat metallic sheets provided with coinciding apertures, combined with a sheet of absorbent paper, and a sheet of stiff non-absorbent paper, said paper sheets provided with glass receiving apertures coinciding with each other and with the apertures of the metallic 90 sheets but of smaller diameter than the apertures of the metallic sheets, and means for holding said sheets together.

WILLIAM S. HARPSTER.
